DIRECTION SIGNAL SWITCH FOR AUTOMOTIVE VEHICLES

George A. Knapp, DeWitt, N.Y., assignor to R. E. Dietz
Company, Syracuse, N.Y., a corporation of New York

Filed Dec. 31, 1959, Ser. No. 58,882

Term of patent 14 years

(Cl. D14—6)

FIG. 1

FIG. 2

FIG. 3

FIGURE 1 is a front elevation of a direction signal switch for automotive vehicles embodying my new design;

FIGURE 2 is a side elevation thereof; and

FIGURE 3 is a front perspective view thereof.

I claim:

The ornamental design for a direction signal switch for automotive vehicles, substantially as shown.
